COIN HANDLING MACHINE

Clarence F. Rogier, Chicago, Thomas E. Kulo, Glenview, and Joseph Singer, Chicago, Ill., assignors to Johnson Fare Box Company, Chicago, Ill., a corporation of Delaware

Application April 18, 1952, Serial No. 282,966

9 Claims. (Cl. 198—37)

This invention relates to a coin handling machine, more specifically it relates to a mechanism for conveying coins from a low to a high bulk coin storage and for cleaning said coins prior to delivery to said high storage.

It is an object of the invention to provide an apparatus which will handle coins without jamming.

Another object of the invention is to provide means for removing loose dirt from the coins.

Yet another object of the invention is to provide means for stopping the conveyor when the high level storage is filled.

A further object of the invention is to provide a vibrator mechanism which assists in the feeding of the coins.

These and other objects will appear from a study of this specification and the drawings which are attached hereto, made a part hereof and in which:

Figure 1 is a side elevation of the apparatus as a whole.

Figure 2 is a plan view of the apparatus of Figure 1.

Figure 3 is a sectional view taken on the line 3—3 of Figure 2 showing the conveyor and coin guiding mechanism.

Figure 4 is a sectional view of the means for actuating coin pushers taken substantially on the line 4—4 of Figure 3.

Figure 5 is a sectional view of the drive mechanism 40 for the pushers, taken substantially on the line 5—5 of Figure 3.

Figure 6 is a sectional view of the clutch mechanism taken substantially on the line 6—6 of Figure 5.

Figure 7 is a sectional view taken substantially on the line 7—7 of Figure 1 showing the vacuum cleaner nozzle and coin chute.

Figure 8 is a sectional view taken on the line 8—8 of Figure 7 showing the vacuum cleaner nozzle.

Figure 9 is an elevation, partly in section, showing another part of the pusher drive.

Figure 10 is a view of the hopper switch mechanism.

Figure 11 is a wiring diagram.

Counter

Referring to Figure 1, the numeral 1 represents a stand upon which is mounted a coin counter 3 of the kind shown in the application of Thomas E. Kulo et al., Serial No. 114,504, filed September 8, 1949, for Coin Counter. This mechanism is provided with a hopper 5 in which is installed a level limit switch 7.

Chute

Adjacent the stand 1 is a mechanism which comprises a frame 9 made up of side plates 11, 13 suitably held together in spaced relation by tie bolts 15. Mounted at the top of the frame by suitable fasteners 16 is a chute 17 which extends downwardly and laterally (Figs. 1 and 2) to discharge into the hopper 5.

Vacuum cleaner

As shown in Figures 1, 7 and 8, means are provided

2

for vacuum cleaning the coins as they pass through the chute. These means comprise a suction device 19 which is a cylindrical tube 20 which has one end supported by a washer 21 and a dished disc 23 which are held in place by screws 25. The other end of the tube is supported in an opening 27 in the side of the chute 17.

A slot 29 is formed in the lower side of the tube 20 and an outwardly diverging nozzle 31 is welded in the slot as shown in Figure 8.

10 A combined vacuum fan and electric motor is indicated by numeral 33. The fan discharges into the filter 35. A hose 37 connects the inlet of the fan with the tapered portion 39 of the suction device 19.

The hose 37 may easily be removed from the portion 15 39 and fitted with a floor tool so that it may be used for cleaning up the floor around the machine.

Conveyor

20 As shown in Figures 1 and 7, slots 41 are formed in the frame plates 11, 13 and a shaft 42 projects therethrough. The shaft has flats 43 milled on each side at the ends thereof which ride in the slots and prevent both axial displacement and rotation of the shaft.

25 A threaded bracket 45 is fixed to each plate and receives an adjusting screw 47 which bears at one end on the shaft 42 to urge it upwardly in the slot. A lock nut 49 on the screw holds the shaft in its adjusted position.

A pair of sprockets 51 are rotatably mounted in spaced relation on the shaft.

30 A pair of spaced guide rails 53 are fixed to the upper portions of the side plates and a pair of spaced rails 55 are fixed to the lower portions of the side plates to serve as guides for the rolls 57 of the chains 59.

35 As shown, particularly in Figure 5, a shaft 61 is mounted in suitable bearings in the side plates and a pair of sprockets 62 are fixed in spaced relation thereon to receive and drive the chains 59.

The chains are connected transversely by pins or shafts 63 and a continuous series of buckets 65 are hingedly mounted at 67 upon adjacent pairs of pins. The hinges 67 of adjacent brackets interfit on the order of a "piano hinge" so that there will be no openings between the buckets through which coins may drop.

Conveyor drive

As shown in Figure 1, an electric motor 69 is mounted upon the frame and through a gear reduction mechanism 71 drives a sprocket 73, chain 75 and sprocket 77.

50 The sprocket 77 is fixed to the driving member 79 of a clutch (Figs. 5 and 6). This member carries the detents 81 which are urged by springs 82 into engagement with notches 83 of the driven member 85 which is fixed to shaft 61.

55 Thus, should the resistance torque of the shaft 61 increase beyond a predetermined amount, the clutch will slip and prevent damage to the various components.

Coin pusher drive

60 The other end of shaft 61 carries a pinion 87 which meshes with a gear 89 (Figs. 5 and 9) which is fixed to a shaft 91 which runs parallel to shaft 61 between the side plates.

The gear 89 carries a crank pin 93 which is connected 65 by a link 95 to the pin 97 of a crank 99 fixed to shaft 101. As the gear 89 revolves, the crank 99 will be oscillated between the positions shown in Figure 9. A suitable cover 100 may be provided for this mechanism.

66 Shaft 101 oscillates the gear 103 which meshes with gear 105 on shaft 107. A bracket 109 (Fig. 3) is fixed to the deck plate 111 which extends between and is fixed horizontally on the side plates and supports the shaft 107.

The shaft carries spur pinion 113 at a level above and substantially parallel to the deck plate.

The deck plate 111 has a pair of upstanding, spaced ribs 115 which run substantially parallel to the conveyor and which are offset outwardly at 117. Ribs 119 extend laterally from the exterior of the ribs and a coin hopper 121 is fixedly mounted on the ribs by suitable supporting means. Cover plates 123, 125 mounted on the ribs serve to enclose the mechanism. A stop plate or gate 127 extends down from the back portion of the hopper and serves as a gate to prevent coins from moving to the right (Fig. 3).

The deck plate terminates at 129 above the conveyor buckets.

A pair of pusher bars 131, 133 fill the space between the ribs 115 and lie flat on the deck plate. Their upper surfaces are very close to gate 127. Attached to the pushers 131, 133 by screws 135 are the racks 137, 139 which mesh with the gear 113. As the gear 113 oscillates, the pusher bars will alternate by moving from a position adjacent the gate 127 (Fig. 3) as illustrated by 131 to a position over the edge as shown by 133 in Fig. 4.

An adjustable gate 141 is slidably mounted on the wall of the hopper opposite gate 127. It is guided at the lower edge of the hopper by washers 143 mounted on pins 145 in the hopper and by a slot 147 in the gate which slidably receives a stud 149 on which is mounted a wing-nut 151.

The upper end of this gate is preferably bent upwardly at 153 to afford a finger hold. Thus the outlet opening 155 of the hopper may be adjusted to restrict the flow of coins to the conveyor.

An electric vibrator 157 is mounted on the hopper to insure that the coins feed down to the outlet thereof.

Cover

A cover of transparent material 159, preferably a transparent plastic, is fixed to the side plates of the frame and extends from the cover plate 125 (Fig. 3) over the top of the conveyor to a position which is indicated by the line 161.

A separate cover 163 of similar material is mounted over the chute 17, as is shown in Figures 1 and 7. Thus, all access to the coins is denied from the low level hopper 121 to the high level hopper 5.

Wiring diagram

The power supply to the motors and vibrator is shown in the wiring diagram, Figure 11, wherein the numeral 167 represents a plug connector. The hot wire is represented by 169 while the neutral wire is 171. A master switch 170 may be used.

The level limit switch 7 is introduced in line 169 ahead of relay magnet 173. The conveyor motor 69 is connected to lines 169, 171 through relay contact 178 and wire 176 and vibrator 157 is connected to lines 169, 171 through relay contact 178 and rheostat 180. The rheostat varies the intensity of vibration to suit the size of coins being handled.

The vacuum cleaner motor 33 is connected directly across lines 169, 171 through a manual switch 183 and line 174. A line 182 connects line 174 between switch 183 and the motor with relay contact 175.

When switch 170 and the limit switch 7 are closed, both motors 69, 33 and vibrator 157 operate due to the closing of the normally open relay contacts 175, 178. As soon as the upper hopper fills, the limit switch is opened and the apparatus stops.

However, should it be desired to operate the vacuum cleaner alone, the switches 170 and 183 may be closed.

As will be seen from Figure 10, the limit switch 7 is a normally closed switch to the lever 185 of which is attached an actuator 187 in the form of a cup which projects into the hopper through an opening therein. Depression of the cup by coins in the hopper opens switch 7.

The electrical structure not otherwise mounted is housed in the box 191, Fig. 1.

Operation

The coins which have been sorted as to denomination and preferably for mutilation are emptied into the hopper 121 and if the level switch 7 is closed, closing of the master switch 170 will start the motor 33, 69 and the vibrator 157.

Coins are fed from the hopper at a rate depending upon the setting of gate 141 onto the pushers 131, 133. The latter are actuated from motor 69 through the chain drive 73, 75, 77, clutch 79, 81, 83, 85, shaft 61, gears 87, 89, crank 93, link 95, crank 99, shaft 101, gears 103, 105, shaft 107, gear 113 and racks 137, 139.

The pushers feed coins into the buckets 65 of the conveyor which are driven from shaft 61 by sprockets 62.

The coins are emptied from the buckets onto the chute 17 at the top of the conveyor and pass by gravity down the chute, underneath the vacuum cleaner nozzle where all loose dirt is removed.

The chute 17 may be perforated, if desired, so that air may enter the chute. Also some of the foreign matter may fall through the chute.

After cleaning, the coins pass into the coin counter hopper 5 until the level of coins therein reaches and depresses the cup 187 to open the switch 7 whereupon the machine is stopped.

Should it be desired to operate the vacuum cleaner separately, while the level switch 7 is open, the switch 183 may be closed and the hose 37 may be used to clean up around the machine.

It is obvious that various changes may be made in the form, structure and arrangement of parts without departing from the spirit of the invention. Accordingly, applicants do not desire to be limited to the specific embodiment disclosed herein primarily for purposes of illustration; but instead they desire protection falling fairly within the scope of the appended claims.

What we claim to be new and desire to protect by Letters Patent of the United States is:

1. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, and pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions, said means serving to move said bars between a position uncovering said platform to said opening and a position covering said platform and extending beyond the discharge edge thereof.

2. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions, said means serving to move said bars between a position uncovering said platform to said opening and a position covering said platform and extending beyond the discharge edge thereof, and a gate extending from said hopper to and in sealing relation with the bars to prevent movement of coins away from the discharge edge of the platform.

3. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, and pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions.

4. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions comprising a gear, a rack on each bar contacting the gear on opposite sides thereof, and means for oscillating the gear.

5. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions comprising a gear, a rack on each bar contacting the gear on opposite sides thereof, means for oscillating the gear comprising a motor, a crank and link mechanism, and means connecting said mechanism to actuate the gear.

6. In a coin handling machine, a bucket type conveyor, means supporting said conveyor for lifting coins from one level to a higher level, a hopper, having a discharge opening disposed at the bottom end of the conveyor, a platform disposed beneath the opening and adjacent the conveyor and having a discharge edge, pusher means for moving coins from said platform, over said edge, into the conveyor buckets, said pusher means comprising a pair of pusher bars, means for guiding the bars on the platform for reciprocation thereon between the hopper discharge opening and the platform, means for reciprocating said bars in opposite directions comprising a gear, a rack on each bar contacting the gear on opposite sides thereof, means for oscillating the gear comprising a motor, a crank and link mechanism, means connecting said mechanism to actuate the gear, and means connecting the motor to drive the conveyor.

7. In a coin handling machine, a bucket type conveyor, means supporting said conveyor for lifting coins from one level to a higher level, a hopper having a discharge opening disposed at the bottom end of the conveyor, a platform disposed beneath the opening and adjacent the conveyor and having a discharge edge, pusher means for moving coins from said platform over said edge and into the conveyor buckets, said pusher means comprising a plurality of elongated flat plates arranged side-by-side, said plates receiving and supporting coins fed from said hopper, means for simultaneously moving said pusher plates longitudinally and in opposite directions alternately from a position adjacent said hopper discharge opening to a position over the discharge edge

of said platform, a gate mounted on said hopper and movable with respect to said discharge opening, said gate being adjustable to vary the effective size of said opening, and a vibrator mounted on said hopper and operable to cause coins to move from said hopper toward said discharge opening.

8. In a coin handling machine, a bucket type conveyor comprising a plurality of conveyor buckets supported for movement, means supporting said conveyor for lifting coins from one level to a higher level, a hopper having a discharge opening adjacent the bottom end of the conveyor, pusher means arranged beneath said discharge opening for receiving and moving coins fed from said hopper, an adjustable gate arranged adjacent and cooperating with said discharge opening for controlling the passage of coins fed to said pusher means through said discharge opening, said pusher means comprising a plurality of elongated coin supporting members arranged side-by-side and extending from beneath said hopper discharge opening to the lower end of said conveyor, means for simultaneously moving said coin supporting members longitudinally relative to each other and in opposite directions to discharge coins deposited thereon into the conveyor buckets, vibrator means connected to said hopper and operable to cause coins to move toward said hopper discharge opening, and a relatively wide chute disposed adjacent the upper end of said conveyor and in position to receive coins discharged from said conveyor buckets, said chute having a bottom which is perforated to effect the discharge of foreign particles dislodged from said coins.

9. In a coin handling system, the combination of a conveyor having buckets arranged thereon, means for supporting said conveyor for lifting coins from one level to a higher level, a hopper having a discharge opening adjacent the bottom end of said conveyor, pusher means for receiving and moving coins therealong fed from said hopper and discharging the same into the conveyor buckets, said pusher means comprising a plurality of elongated plates arranged side-by-side, means for simultaneously moving said plates longitudinally and in opposite directions with respect to adjacent plates alternately from a position adjacent the discharge opening of said hopper and to a position to discharge said coins into said conveyor buckets, means for driving the conveyor, a chute disposed for receiving coins discharged from said conveyor buckets at said higher level, a second hopper positioned to receive coins discharged from said chute, a coin level switch for starting and stopping said conveyor driving means which is actuated in response to predetermined high and low levels of coins in said second hopper.
